UNITED STATES PATENT OFFICE.

SYLVESTER L. GOOKIN, OF BOSTON, MASSACHUSETTS, ASSIGNOR TO UNITED SHOE MACHINERY CORPORATION, OF PATERSON, NEW JERSEY, A CORPORATION OF NEW JERSEY.

EYELETING-MACHINE.

1,368,334.

Specification of Letters Patent. Patented Feb. 15, 1921.

Application filed May 21, 1918. Serial No. 235,828.

To all whom it may concern:

Be it known that I, SYLVESTER L. GOOKIN, a citizen of the United States, residing at Boston, in the county of Suffolk and State 5 of Massachusetts, have invented certain Improvements in Eyeletting-Machines, of which the following description, in connection with the accompanying drawings, is a specification, like reference characters on the drawings indicating like parts in the several 10 figures.

This invention relates to eyeletting machines and more particularly to the eyelet presenting and setting mechanisms of such 15 machines.

One method of setting blind or invisible eyelets involves the use of an expandible die or set of the type illustrated in United States Letters Patent No. 1,271,720, granted 20 July 9, 1918, on an application of H. W. Kenway. The sections of such a set are provided with a shoulder upon one side of which is an upsetting surface and in use the shoulder is located between the layers of a 25 piece of work such, for example, as the upper of a shoe, so that the eyelet is clenched over only a part of the layers of the work. A die or set of the type above outlined is frequently used as the spindle of the eyelet 30 presenting set and in such cases it is arranged to thread the endmost eyelet in the supplying raceway to remove the eyelet from the raceway and to guide the eyelet to the companion setting tool. It will be understood that in such an arrangement the 35 spindle must necessarily be of a size to pass through the barrel of the eyelet and consequently its sections are very delicate and are liable to be broken in case the expandible set 40 or spindle encounters an improperly positioned eyelet or an eyelet whose barrel is clogged or imperfectly formed.

An important object of the invention is to provide an improved expandible set in 45 which the liability of breakage shall be minimized.

A feature of the invention consists in an expandible set in which the relatively movable, normally contracted sections are inter- 50 connected at both ends.

Machines employing expandible sets have commonly been provided with means for expanding said sets arranged externally of the sets. In United States Letters Patent 55 No. 1,297,695, granted March 18, 1919, on

an application of Ralph F. Knight, there is illustrated an expandible set which is provided with a tubular body and with a die expanding member passing through the bore of the body. This member is controlled by 60 yielding means arranged to bear against the upper end of the expanding member in order to force it into the die and by other yielding means arranged below the end of the die expanding member for forcing it 65 out of the die. Such an arrangement, however, sometimes involves difficulties because of its lack of positive control.

Another feature of the present invention consists in arranging the die expanding 70 member of the expandible set so that it shall be positively controlled. In the illustrated construction, the eyelet presenting set, the expandible set, and the die expanding member are initially located on one side of the 75 work and they are all arranged to be controlled from this side.

These and other features will be more fully described in the following specification taken in connection with the accompanying drawing, in which,—

Figure 1 is an angular view of the front end of an eyeletting machine embodying the present invention;

Fig. 2 is a vertical section through the 85 eyelet setting mechanisms; and

Fig. 3 is an enlarged view of the expanding set and its associated expanding member.

The present invention may be applied to various types of machines but the construction and arrangement of the parts not herein illustrated may well be similar to the construction of the corresponding parts of the machine illustrated in Letters Patent of the United States No. 603,023, granted April 26, 90 1898, upon an application of Seymour Field, to which reference may be had for further description of the parts not herein shown. Such a machine embodies a work supporting table 10 upon which the work is held in 100 place by means of a suitable presser foot 12.

Above this table is arranged a punch lever 14 and a feeding lever 16 which, in the operation of the machine, are constructed and arranged to punch a hole in the work and 105 then to move the work laterally by a predetermined amount to bring the punched hole into alignment with the eyelet setting mechanism. In the present arrangement, a tubular tool 18 is carried by and fixed to the lever 110

16, and the feeding finger 20 is resiliently mounted within said tool, as more fully shown in Fig. 2.

5 Mounted in suitable bearings for reciprocation below the work table is a plunger 30 provided at its lower end with a cam roll 32 arranged to engage with a cam track in a cam 34 mounted upon the main shaft 36 of the machine. This plunger carries at its 10 upper end an eyelet presenting set 38 within which is mounted an expansible set 40. This expansible set projects above the set 38 and acts as a spindle for the removal of eyelets from a raceway 42 and as a guiding means 15 for insuring the presentation of the eyelet to the previously punched hole of the work. The lower end of the set 40 is threaded into an angular piece 44 which projects outwardly through a slot in the side of the plunger 30 and is reciprocated with the 20 plunger 30. This angular piece 44 and the set 40 are resiliently supported by means of a spring 46 received within a recess of the plunger and vertical movement of the expanding set is limited by the engagement of the angular piece 44 with an adjustable stop 48 clamped in an inclined slot in the frame 25 of the machine.

It will be noted that the expansible set of 30 applicant's novel construction is provided with a tubular body having an internal bore originally of substantially uniform cross section. Longitudinal slits 50 through the sides of the tubular body and spaced from 35 the ends thereof provide for the expansion and contraction of the sections formed by said slits. It will be understood that one way of manufacturing the expansible set is to spin the sections into contacting relation 40 after the tubular body has been slotted and then to temper the body so that the sections are normally contracted but may be expanded when desired. At a point intermediate the ends of the sections and upon their 45 outer surface, there is provided a shoulder 52 one surface of which, in this case the lower surface 54, is formed as an upsetting surface. The construction of the expansible set is preferably such that the outer diameter of the shoulder 52, when the set is contracted, is no greater than the internal diameter of the outer end of the tubular body. A die expanding member 60 is then provided which is arranged within the bore of 50 the tubular body. This expanding member is preferably constructed as a rod of substantially uniform cross section designed to fit the bore of the tubular body and is provided at its lower end with a cam roll 62 55 arranged in engagement with a track in the cam 34 and adapted to be positively actuated from said cam. A suitable slot 64 is provided in the plunger 30 to allow interconnection of the cam roll with the rod 60. 60 The upper end of the expanding member is

preferably rounded and when the expanding set 40 is in position to thread the endmost eyelet in the raceway, this rounded head projects slightly above the end of the set, as shown in Fig. 1, and assists in centering the eyelet. Intermediate its ends the member 60 is constructed at 66 to such a size that when this portion is positioned opposite the shoulder 52 it allows the complete contraction of the movable sections of the die 40. When, however, another portion of the expanding member 60 is positioned opposite the shoulder 52, as shown in Fig. 2, it will be seen that the movable sections of the die are expanded to make the upsetting surface 80 upon the lower side of the shoulder effective. As the parts move into the relation shown by Fig. 2 the upper end of the expansible tool 40 enters the bore of the tool 18, thereby pushing the lower end of the 85 feeding tool 20 into the tool 18. The tool 40 is thus braced at its upper end by the tool 18 although the shoulder portions 52 which remain outside the tool 18 are capable of being forced apart as far as the latter will 90 permit. The tool 40 at this time extends through all the layers of the work, and the tool 18 serves as an abutment for the upper layer of the work.

In the operation of the machine, the insertion of the upper end of the die 40 into the abutment 18 may be partially effected before the raceway is moved laterally to withdraw the endmost eyelet therefrom and, by reason of the support of the die 40 at both of its ends, any danger of breakage from such lateral movement is very greatly reduced. It will be understood that, in the general operation of the machine, both the upper and lower layers 70 and 72 of the 100 work are punched by the tool carried by the lever 14 which then is raised and moved laterally to allow the feeding finger 20 to be inserted in the previously punched hole. A lateral movement of the lever 16, the presser foot 12 having been lifted at this time, feeds the work and brings the hole into alignment with the setting tools 38 and 40. Rotation of the main shaft 36 will have, at this time, also controlled the position of the 105 plunger 30 carrying the set 38 so that the spindle or set 40 will have been threaded through the endmost eyelet in the raceway 42 and, as said raceway is being withdrawn, the outer end of the member 40 will have 110 entered the bore of the abutment 18, as above described. The combined set and spindle 40 will be normally maintained in extended position by the spring 46 until the shoulder 52 has reached the desired position between the layers 70 and 72 of the work, and this position will be positively controlled by the engagement of the angular member 44 with the stop 48. After the 115 expanding set 40 has been positioned with 120 the shoulder 52 has reached the desired position between the layers 70 and 72 of the work, and this position will be positively controlled by the engagement of the angular member 44 with the stop 48. After the 125 expanding set 40 has been positioned with 130

its shoulder at the proper level between the layers of work, the die expanding member 60 will be positively actuated by the cam 34 to bring the die expanding portion there-
 5 of opposite the shoulder 52 and thus to cause the expansion of the movable sections of the die. Obviously this expansion affects the sections both above and below the shoulder 52, and the expansion of the upper
 10 portions within the layer of the work in which the eyelet is not to be set will materially assist in alining the hole in the work accurately with the set 38 and in insuring perfect work. Further elevation of the eye-
 15 let presenting set 38 will then take place and will carry an eyelet along the member 40 until the barrel of the eyelet meets the upsetting surface 54 on the expanded sections and is clenched over the lower layer
 20 72 of the work. The parts of the mechanism will then be separated to free the work, and the cycle of operations may be repeated.

It should be noted that the joining together of the corresponding ends of the expandable sections of the set 40, in this case by making them integral with one another, is of material assistance in reducing breakage of these very delicate parts, especially
 25 at the time when the upper end of the set is threading the endmost eyelet in the race-
 30 way. The entrance of dirt in the interior of the tubular body of the set 40 will be very largely prevented by the continual
 35 presence of the die expanding member 60 therein.

Attention is called to the fact that the novel arrangement described allows the complete control of the eyelet setting mech-
 40 anism from one side of the work. The ex-
 pansible set or die, the eyelet presenting set and the die expanding member are all ini-
 tially located at one side of the work and are continuously controlled from that side.
 45 The feeding member 20 takes no part in the eyelet setting operation with this arrange-
 ment.

Having thus described my invention, what I claim as new and desire to secure
 50 by Letters Patent of the United States is:

1. In an eyeletting machine, an expandible upsetting die, and means for presenting said die to one side of the work, said die comprising expandible normally contracted sec-
 55 tions and an upsetting surface formed upon the sections, said sections being joined integrally at that end of the die which is pre-
 sented to the work.

2. In an eyeletting machine, an expandible
 60 upsetting die comprising a spindle having expandible normally contracted sections, and an upsetting surface formed upon these sections, said sections being integral with the spindle at each of their ends.

65 3. In an eyeletting machine, an upsetting

die comprising a tubular body portion having integral ends and provided with longitudinal slits spaced from the ends and forming expandible sections, and an upsetting surface upon said sections. 70

4. In an eyeletting machine, an expandible upsetting die comprising expandible sec-
 75 tions, the corresponding ends of which are integrally connected one with another at each end.

5. In an eyeletting machine, a spindle pro-
 80 vided with integral ends and an intermediate portion comprising expandible sections, a shoulder formed in said sections taken collectively, and an upsetting surface on one side of said shoulder.

6. In an eyeletting machine, an upsetting die comprising a member having normally contracted expandible sections formed to provide a shoulder, one surface of which 85 constitutes an upsetting surface, said sections being extended beyond said shoulder and having means integrally connecting them together.

7. In an eyeletting machine, eyelet setting 90 means comprising an expandible upsetting die having expandible normally contracted sections, means for positioning said die, means for expanding said die, and means for positively controlling said expanding 95 means.

8. In an eyeletting machine, eyelet setting means comprising an expandible upsetting die having expandible normally contracted sections, means for positioning said die, 100 means for expanding said die, and means for positively positioning said expanding means.

9. In an eyeletting machine, a movable eye-
 105 let presenting set, an expandible upsetting die, means for expanding said upsetting die, and means for positively controlling said expanding means.

10. In an eyeletting machine, an expandible upsetting die comprising a tubular body 110 portion having normally contracted expandible sections provided with an upsetting surface, means movable within said upsetting die for expanding said normally contracted sections, and means for positively control- 115 ling said expanding means.

11. In an eyeletting machine, an eyelet set 120 provided with a resiliently expelled spindle, said spindle being provided with an upsetting surface upon a plurality of mov-
 able sections constructed and arranged to be maintained normally in contracted condition, the outer ends of said sections being integrally interconnected with one another.

12. In an eyeletting machine, an upsetting 125 die comprising a tubular body provided with a plurality of movable sections constructed and arranged to be maintained normally in contracted condition, said sections being provided with a shoulder forming an up- 130

- setting surface, and a die-expanding member arranged to remain in the bore of said tubular die and provided with a contracted portion adapted to be positioned adjacent to the shoulder upon said movable sections to allow the contraction thereof and to be moved to another position to cause their expansion into operative position.
13. In an eyeleting machine, a work feeding device arranged upon one side of the work and comprising two telescopically related members, and eyelet presenting and upsetting means arranged on the opposite side of the work and comprising an expansible spindle provided with an upsetting surface upon its expansible portion adapted to be located adjacent to the level of the work and with an extension adapted to enter into telescopic relation with the outer one of said two telescopically related members.
14. In an eyeleting machine, mechanism for setting blind or invisible eyelets comprising an eyelet-inserting tool and a spindle in telescopic relation, the spindle having an expansible portion constructed and arranged to extend through all the layers of the work, and means arranged to expand the spindle while said expansible portion occupies all the layers of the work, the tool and spindle being arranged to set an eyelet in one of said layers but outside another one of the layers while said expansible portion is expanded and occupying all the layers.
15. In an eyeleting machine, means for supplying eyelets, eyelet-setting mechanism comprising co-operative eyelet-engaging tools including a spindle having an expansible portion constructed and arranged to take an eyelet from said supplying means and then to extend through all the layers of the work, and means arranged to expand the spindle while said portion occupies all the

layers of the work and prior to the setting of the eyelet, thereby to maintain registration of the layers during the setting operation. 45

16. In an eyeleting machine, eyelet setting means comprising eyelet presenting means, an expansible set and set expanding means, and means for controlling said presenting means and said expanding means from one side of the work. 50

17. In an eyeleting machine, eyelet setting means comprising an expansible set movable through a portion of the work and set expanding means, and means for controlling the operation of said expansible set and said set expanding means from one side of the work. 55

18. In an eyeleting machine, eyelet setting means comprising eyelet presenting means, an expansible set movable through a portion of the work, set expanding means, and means for controlling the operation of said presenting means, expansible set and set 60 expanding means from one side of the work. 65

19. In an eyeleting machine, eyelet-setting mechanism comprising a setting tool, a raceway for supplying eyelets, a spindle associated with said tool to remove an eyelet from the raceway and to maintain the eyelet in registration with said tool, and a tubular tool arranged to embrace the leading end of the spindle while the latter is threaded through an eyelet in the raceway, 70 said tubular tool being effective to brace the spindle against lateral stress while the raceway and the spindle undergo relative movement to remove the eyelet from the raceway. 75

80 In testimony whereof I have signed my name to this specification.

SYLVESTER L. GOOKIN.
